OF LONDON, ENGLAND.

REEL-BRAKE FOR WEB-PRINTING MACHINES.

1,241,759.

Specification of Letters Patent.

Patented Oct. 2, 1917.

Application filed January 25, 1915. Serial No. 4,128.

To all whom it may concern:

Be it known that we, THOMAS ROBERT GILLETT PARKER, WILLIAM EDWARD BENNISON, and WALTER LEE, subjects of the King of the United Kingdom of Great Britain and Ireland, residing at Linotype and Machinery Works, Broadheath, in the county of Chester, England, have invented new and useful Improvements in Reel-Brakes for 10 Web-Printing Machines, of which the following is a specification.

This invention relates to reel brakes for web printing machines and it has for its object to provide brakes of such construction 15 as to enable the empty reel spindles to be removed from the machines and new reels to be placed in the machines more expeditiously than has hitherto been possible with existing devices.

20 In machines printing upon a web, it is necessary to keep the web taut and consequently brake devices are employed for preventing the reel from turning too quickly, these devices bearing frictionally upon 25 either the reel itself or upon the reel spindle.

When the brake is one which involves the application of friction to the reel spindle, it has heretofore generally been in the form of a brake band attached to the machine frame, 30 encircling a brake drum fast on the said spindle, the pressure of the band on the drum being regulated by means of a screw. Brakes of this construction involve the loss of considerable time during the operation 35 of removing an empty reel spindle from, and inserting a new reel in, the machine, owing to the fact that for each such operation it is necessary first to uncouple and afterward to couple the brake.

40 By means of the present invention the necessity for the just mentioned uncoupling and coupling is entirely avoided and consequently the time necessary for inserting a new reel into the machine is greatly reduced.

45 In the accompanying drawings, Figure 1 is a plan and Fig. 2 an elevation of the new reel brake mechanism, certain parts in the latter view being, for convenience, conventionally represented in positions other than 50 those in which they are shown in Fig. 1.

Referring to these drawings, 1 is a grooved brake drum fast on the reel spindle 2, which is gripped, with an adjustable pres-

sure, between the two wooden or equivalent 55 blocks or brake-shoes 3, 4.

These brake-shoes are carried respectively by the arms 5, 6, of two brake jaws (which numerals are hereinafter employed to identify the respective brake jaws when these 60 are referred to as complete entities), the other arms 7, 8, of which are pivoted on a horizontal shaft 9, which turns, but is fixed against axial movement in bearings 10, 11, (Fig. 1) and has fast on it a hand wheel 12 65 by which it can be rotated. The said shaft is parallel with the reel spindle and is screw-threaded to engage with the correspondingly screw-threaded bosses of the arms 7, 8, so that when it is rotated the brake jaws 5, 6, 70 are moved in the direction of its axis, which movement, being transmitted through the brake drum 1, effects axial adjustment of the reel spindle 2 and the reel thereon to obtain 75 correct register of the web.

The two brake jaws 5, 6, are operatively connected, by devices hereinafter described, with the pressure adjusting mechanism which comprises a vertical rod or shaft 13, having left and right-handed screwed portions 80 respectively engaging correspondingly threaded nuts 14, 15. The shaft 13 can be rotated by a hand wheel 16 fast thereon, or through gearing or like mechanism, such as 17, connecting it with a hand wheel or 85 equivalent situated at the folder end or other remote part of the machine. The nuts 14, 15, are held against rotation on the shaft 13 by the devices connecting them with the brake jaws 5, 6, so that rotation of the said shaft 90 will cause them to move in relatively opposite directions, thereby increasing the pressure of the brake-shoes 3, 4, on the brake drum 1, according to the direction of such 95 rotation.

The connection between the lower brake jaw 5 and the nut 14 is made through a bipartite arm, 18, 19, the part 18 of which is pivoted to the said jaw by a vertical stud 20 and axially swiveled at 21 to the part 19 100 (hereinafter referred to as a fork,) which latter is forked both vertically and horizontally so as to embrace two sides of the nut 14 and studs 22, 23, projecting therefrom, thereby establishing an effective connection 105 between the said fork 19 and nut 14 and yet allowing the former to freely turn and slide relatively to the latter.

The connection between the upper brake jaw 6 and nut 15 is effected by means of a tri-partite arm 24, 25, 26, the last-mentioned part (26—hereinafter referred to as a fork) being a replica of the fork 19 just described, connected to the nut 15 in the same manner as the said fork 19 is connected to its nut 14, and axially swivelled at 27 to the part 25. The part 24 is pivoted to the brake jaw 6 by 10 a vertical stud 28, and it is also pivoted, horizontally at 29, to the part 25. A further connection between the two parts 24 and 25 is, however, necessary to secure the maintenance of rigidity between the said parts when the brake jaw 6 is adjusted as 15 will be subsequently described, either in its operative position or in the position to which it is moved to allow of the removal of the reel. The last-mentioned connection which is a rigid and adjustable one, is effected by 20 a plunger 30 which is axially movable under and against the action of a spring 31 in the part 25, and adapted to engage with either of two holes 32, 33, in the part 24.

25 It will be seen that the brake jaw 5 with its arm 7, and the parts 18, 19, constitute what is virtually a lower brake lever capable of rocking about the axis of the shaft 9 and that the brake jaw 6 with its arm 8, and the 30 parts 24, 25 and 26, similarly constitute an upper brake lever capable of rocking about the same axis; as a matter of convenience the term "brake lever," as hereinafter employed, is intended to refer to a combination 35 of parts which, as a whole, is capable of rocking about the axis of the shaft 9.

In an apparatus provided with the foregoing devices, a change of reel is effected as follows. The pressure of the brake-shoes 40 3, 4, on the brake drum 1 is first released by rotating the shaft 13 in the direction necessary to cause a movement of the nuts 14, 15, toward each other, this movement effecting a rocking of the upper and lower brake levers on their pivot 9, thus bringing the shoes 45 3, 4, out of frictional contact with the brake drum 1. The plunger 30 is then manually withdrawn from the hole 32, thus disestablishing the rigid connection between the parts 25 and 24, and enabling the upper 50 brake jaw 6 and the part 24 to be swung freely, as a single entity, on the pivot 9, the forked end of the part 26 meanwhile pivoting and sliding upon the studs fast to the respective nut 15, until the arms 6 and 8 and 55 parts 24, 25 and 26 assume the positions in which they are respectively shown in dot-and-dash lines in Fig. 2, at which juncture the plunger 30, under the action of the 60 spring 31, automatically engages the hole 33 then presented to it, thereby temporarily locking all the parts in the last-mentioned position. The reel spindle 2 may then be 65 lifted and moved away to make room for the insertion of a new reel. After a new reel

has been inserted, the series of operations just described is carried out in the reverse order.

Having described our invention, we declare that what we claim and desire to secure by Letters Patent is:

1. In a reel brake, the combination with a 70 brake drum and a shaft whose axis is parallel with that of the brake drum, of a brake lever comprising a first part mounted upon, and adapted to rock about the axis of, the said shaft, a second part, and a stud directly pivoting the second part to the first part and having its axis perpendicular to that of the said shaft.

2. In a reel brake, the combination with a 80 brake drum and a shaft whose axis is parallel with that of the brake drum, of a brake lever comprising a first part mounted upon, and adapted to rock about the axis of, the said shaft, a second part pivoted to the first part and adapted to turn about an axis perpendicular to that of the said shaft, and a third part swiveled to the second part and adapted to turn about an axis perpendicular to and intersecting the axis of the pivot 90 which connects together the first and second parts.

3. In a reel brake, the combination with a 90 brake drum and a shaft whose axis is parallel with that of the brake drum, of a brake lever comprising a first part mounted upon, and adapted to rock about the axis of, the said shaft, a second part pivoted to the first part and adapted to turn about an axis perpendicular to that of the said shaft, a third part pivoted to the second part and adapted to turn relatively thereto about an axis lying in a plane perpendicular to that containing the axis of the pivot connecting together the first and second parts, a fourth part swiveled to the third part and adapted to turn about an axis perpendicular to and intersecting the axis of the pivot connecting together the second and third parts, and 100 means for locking together the said second and third parts in different positions relatively to each other.

4. In a reel brake, the combination with a 110 brake drum and a shaft whose axis is parallel with that of the brake drum, of a brake lever comprising a first part mounted upon, and adapted to rock about the axis of, the said shaft, a second part pivoted to the first part and adapted to turn about an axis perpendicular to that of the said shaft, a third part pivoted to the second part and adapted to turn relatively thereto about an axis 115 lying in a plane perpendicular to that containing the axis of the pivot connecting together the first and second parts, a fourth part swiveled to the third part and adapted to turn about an axis perpendicular to and intersecting the axis of the pivot connecting together the second and third parts, 120 125 130

and an adjustable spring plunger adapted to lock together the said second and third parts in relatively different position.

5. In a reel brake, the combination with
5 a brake drum and a shaft whose axis is parallel with that of the brake drum, of a lower brake lever and an upper brake lever each comprising a first part mounted upon, and adapted to rock about the axis of, the
10 said shaft, a second part pivoted to the first part and adapted to turn about an axis perpendicular to that of the said shaft, and a third part swiveled to the second part and adapted to turn about an axis perpendicular
15 to and intersecting the axis of the pivot which connects together the first and second parts, the first part of one of the said levers being adapted to be rocked into different positions about the axis of the said shaft
20 independently of the other lever, means adapted to lock the said first part when so rocked, and means adapted to simultaneously rock both levers about the axis of the said shaft in relatively opposite directions.

25 6. In a reel brake, the combination with a brake drum and a shaft whose axis is parallel with that of the brake drum, of a lower brake lever comprising a first part mounted upon, and adapted to rock about the axis of, the said shaft, a second part pivoted to the first part and adapted to turn about an axis perpendicular to that of the said shaft, and a third part swiveled to the second part and adapted to turn about an axis perpendicular to and intersecting the axis of the pivot which connects together the first and second parts, an upper brake lever comprising a first part mounted upon, and adapted to rock about the axis of, the
35 said shaft, a second part pivoted to the first part and adapted to turn about an axis perpendicular to that of the said shaft, a third part pivoted to the second part and adapted to turn relatively thereto about an axis lying
40 in a plane perpendicular to that containing the axis of the pivot connecting together the first and second parts, a fourth part swiveled to the third part and adapted to turn about an axis perpendicular to and intersecting the axis of the pivot connecting together the second and third parts, and means for locking together the said second and third parts in different positions relatively to each other, and means adapted to simultaneously rock
55 both the levers in relatively opposite directions about the axis of the said shaft.

7. In a reel brake, the combination with a brake drum and a shaft whose axis is parallel with that of the brake drum, of a lower brake lever comprising a first part mounted upon, and adapted to rock about the axis of, the said shaft, a second part pivoted to the first part and adapted to turn about an axis perpendicular to that of
60 the said shaft, and a third part swiveled to

the second part and adapted to turn about an axis perpendicular to and intersecting the axis of the pivot which connects together the first and second parts, an upper brake lever comprising a first part mounted upon, and adapted to rock about the axis of, the said shaft, a second part pivoted to the first part and adapted to turn about an axis perpendicular to that of the said shaft, a third part pivoted to the second part and adapted to turn relatively thereto about an axis lying in a plane perpendicular to that containing the axis of the pivot connecting together the first and second parts, a fourth part swiveled to the third part and adapted to turn about an axis perpendicular to and intersecting the axis of the pivot connecting together the second and third parts, and an adjustable spring plunger adapted to lock together the said second and third parts
70 in relatively different positions, and means adapted to simultaneously rock both the levers in relatively opposite directions about the axis of the said shaft.

8. In a reel brake, the combination with a
90 brake drum and a shaft whose axis is parallel with that of the brake drum, of a lower brake lever and an upper brake lever each comprising a first part mounted upon, and adapted to rock about the axis of, the said shaft, a second part pivoted to the first part and adapted to turn about an axis perpendicular to that of the said shaft, and a third part swiveled to the second part and adapted to turn about an axis perpendicular to and intersecting the axis of the pivot which connects together the first and second parts, and means adapted to simultaneously rock both the levers in relatively opposite directions about the axis of the said shaft.

9. In a reel brake, the combination with a
95 brake drum and a shaft whose axis is parallel with that of the brake drum, of a lower brake lever comprising a first part mounted upon, and adapted to rock about the axis of, the said shaft, a second part pivoted to the first part and adapted to turn about an axis perpendicular to that of the said shaft, and a third part swiveled to the second part and adapted to turn about an axis perpendicular to and intersecting the axis of the pivot which connects together the first and second parts, an upper brake lever comprising a first part mounted upon, and adapted to rock about the axis of, the said shaft, a second part pivoted to the first part and adapted to turn about an axis perpendicular to that of the said shaft, a third part pivoted to the second part and adapted to turn about an axis perpendicular to and intersecting the axis of the pivot which connects together the first and second parts, and means for locking together the said second and third parts in different positions relatively to each other, and means adapted to simultaneously rock both the levers in relatively opposite directions about the axis of the said shaft.

10. In a reel brake, the combination with a
110 brake drum and a shaft whose axis is parallel with that of the brake drum, of a lower brake lever comprising a first part mounted upon, and adapted to rock about the axis of, the said shaft, a second part pivoted to the first part and adapted to turn about an axis perpendicular to that of the said shaft, and a third part swiveled to the second part and adapted to turn relatively thereto about an axis lying in a plane perpendicular to that containing the axis of the pivot connecting together the first and second parts, a fourth part swiveled to the third part and adapted to turn about an axis perpendicular to and intersecting the axis of the pivot which connects together the first and second parts, and means for locking together the said second and third parts in different positions relatively to each other, and means adapted to simultaneously rock both the levers in relatively opposite directions about the axis of the said shaft.

- axis of the pivot connecting together the second and third parts, and means for locking together the said second and third parts in different positions relatively to each other,
- 5 5. a rotatable shaft, two respectively right-hand and left-hand screw-threaded portions on the said rotatable shaft, correspondingly screw-threaded nuts in engagement with the said portions, and connections between the
- 10 10. said nuts and the respective brake levers adapted to hold the nuts against rotation and transmit to the levers the motion imparted to the nuts by the rotation of the shaft.
- 15 15. 10. In a reel brake, the combination with a brake drum, of a rotatable, screw-threaded shaft whose axis is parallel with that of the brake drum, and two brake levers each comprising a first part having a boss in screw-threaded engagement with and turnable on the said shaft, a second part pivoted to the first part and adapted to turn about an axis perpendicular to and intersecting that of the said shaft when such shaft is turned, and a
- 20 20. third part swiveled to the second part and adapted to turn about an axis perpendicular to and intersecting the axis of the pivot which connects together the first and second parts.
- 25 25. 11. In a reel brake, the combination with a brake drum, of a rotatable, screw-threaded shaft whose axis is parallel with that of the brake drum, two brake levers each comprising a first part having a boss in screw-threaded engagement with and turnable on the said shaft, a second part pivoted to the first part and adapted to turn about an axis perpendicular to and intersecting that of the said shaft when such shaft is turned, and a
- 30 30. third part swiveled to the second part and adapted to turn about an axis perpendicular to and intersecting the axis of the pivot connecting together the first and second parts, the first part of one of the said levers
- 35 35. being adapted to be rocked into different positions about the axis of the said shaft independently of the other lever, means
- 40 40. 45. 45.

adapted to lock the said first part when so rocked, and means adapted to simultaneously rock both levers about the axis of the said shaft in relatively opposite directions.

12. In a reel brake, the combination with a brake drum, of a rotatable, screw-threaded shaft whose axis is parallel with that of the brake drum, a lower brake lever comprising a first part having a boss in screw-threaded engagement with and turnable on the said shaft, a second part pivoted to the first part and adapted to turn about an axis perpendicular to and intersecting that of the said shaft when such shaft is turned, and a third part swiveled to the second part and adapted to turn about an axis perpendicular to and intersecting the axis of the pivot which connects together the first and second parts, an upper brake lever comprising a first part, a boss on the said first part threaded and turnable on the said shaft, a second part pivoted to the first part and adapted to turn about an axis perpendicular to and intersecting that of the said shaft, a third part pivoted to the second part and adapted to turn relatively thereto about an axis lying in a plane perpendicular to that containing the axis of the pivot connecting together the first and second parts, a fourth part swiveled to the third part and adapted to turn about an axis perpendicular to and intersecting the axis of the pivot connecting together the second and third parts, and an adjustable spring plunger adapted to lock together the said second and third parts in relatively different positions, and means adapted to simultaneously rock both the levers in relatively opposite directions about the axis of the said shaft.

In witness whereof we have hereunto set our hands in the presence of two witnesses.
